BOTTLE CARRIER

George H. Allington and Joseph M. Grzelak, Rockford, Ill., assignors of forty per cent to George H. Allington, thirty per cent to Joseph M. Grzelak, and thirty per cent to Wesley Beckovich, Rockford, Ill.

Application November 5, 1945, Serial No. 626,615

12 Claims. (Cl. 224—45)

1

This invention relates to bottle carriers for use with the familiar small necked soft drink bottles.

Innumerable designs and constructions of carriers for pop bottles have been proposed, but the majority of them are too complicated and expensive and many have been objectionable from the standpoint that they will not permit stacking the bottles in carriers for display purposes. It is therefore the principal object of our invention to provide a bottle carrier made of the fewest possible number of parts, to-wit, a base on which to rest the bottles and opposed handle bails pivoted to the opposite sides of the base and arranged to be quickly and easily interlocked at their upper ends to form a convenient handle for carrying, all three parts being of extremely simple and economical, but nevertheless thoroughly serviceable, construction.

A salient feature of the present carrier is the sliding pivotal connections for the lower ends of the bails on the base which permits raising the interlocked bails to carrying position with the handle in raised relation to the tops of the bottles, the bails otherwise being disposed in a lowered position with the carrying handle disposed between the necks of the bottles and below the level of the caps thereon so that the carriers with bottles therein may be stacked for display purposes, making it convenient for the customers and clerks to handle the same.

Another feature is the interlocking of the handles in a novel manner to facilitate carrying the carrier.

The invention is illustrated in the accompanying drawing, in which—

Fig. 1 is an end view of a bottle carrier made in accordance with our invention showing the handle bails in their lowermost position permitting stacking of carriers, as described, and indicating in dotted lines the raised carrying position of said bails.

Fig. 2 is a side view of Fig. 1.

Fig. 3 is an end view of the carrier on a smaller scale with the bails shown spread apart and indicating in dotted lines how other carriers in similar condition may be placed in stacked relation thereto for shipment of a large number in a compact bundle, and

Fig. 4 is an end view similar to Fig. 1 showing another carrier of modified or alternative construction, the base being made of wire instead of sheet metal.

Similar reference numerals are applied to corresponding parts throughout the views.

2

Referring first to Figs. 1 and 2, the reference numeral 5 designates the one piece U-shaped sheet metal base, and 6 and 7 the wire bails. The base 5 is of generally rectangular form to provide an elongated bottom 8 and upwardly bent end walls 9 and 10 which, as clearly appears in Fig. 2, are in upwardly diverging relationship so as to permit nesting of bases when a number of carriers are to be stacked together in a bundle, as illustrated in Fig. 3, for shipment. The end walls 9 and 10 have vertical slots 11 and 12 punched therein and the bails 6 and 7 have elongated loops or eyes 13 and 14 formed on the lower ends of the generally U-shaped wire frames 15 thereof which are entered loosely in these slots for easy working sliding pivotal connections between the bails and base. These loops 13 and 14 are normally in the lower ends of the slots 11 and 12 so that the cross portions 16 and 17 of the frames of the bails 6 and 7, interlocked by the small lug 18 to form a carrying handle, are disposed between the necks of the bottles in the carrier and below the horizontal plane of the tops of the caps of said bottles, as clearly illustrated in Fig. 1, so that the carriers may be stacked for display purposes in the store, and yet there is no difficulty for the customer or clerk to pick up a carrier inasmuch as the handle is easily accessible and can be raised to carrying position quickly and easily, as indicated in dotted lines in Fig. 1. The compactness of the carrier with the bails in lowered position is also of advantage to the housewife wherever it is desired to place the carrier with the bottles therein in the refrigerator. This carrier by reason of its all-around compact construction takes up very little more room in the refrigerator than the bottles would if removed from the carrier. The bail 6 on which the lug 18 is provided has the cross portion 16 thereof slightly shorter than the cross portion 17 of the bail 7 so as to permit interfitting the upper end of the bail 6 in the upper end of bail 7, after which the cross portion 17 is arranged to be flexed to engage it behind the lug 18 in the manner shown in Fig. 2. This interlocks the handles securely enough so that they will not come apart accidentally and yet they may be easily uncoupled whenever desired.

The frames 15 of the bails 6 and 7 have the legs 19 thereof bent at 20 to provide lower portions 21 which are vertically disposed when the handles are interlocked, and these vertical portions 21 have the ends of parallel horizontal wires 22 and 23 welded thereon to keep the bottles in position on the base by tight contact with the

3

outer sides thereof, there being room enough on the base for two rows of bottles, three in each row. This contact of the wires 22 and 23 with the sides of the bottles incidentally serves to guide the bails in the up and down movement of the bails with respect to the base so that there is no tendency for the loops 13 and 14 to bind in the slots 11 and 12. The extreme lower end portions 24 of the legs 19 in which the loops 13 and 14 are formed are bent substantially at right angles to the adjacent portions 21, and these portions 24 are only long enough to allow room for the two rows of bottles between the wires 22-23 on the two bails 6 and 7 when the bails are in interlocked relationship, allowing only enough for easy up and down movement of the loops 13 and 14 in the slots inasmuch as the freedom of movement of the bails up and down is so important to the proper functioning of the carrier.

The base 5 may have longitudinally extending ribs 25 embossed therein in parallel relation, two under each row of bottles, so that there is good drainage of any moisture and good opportunity for drying and consequently less likelihood of rusting. The ribs 25, furthermore, add stiffness and strength to the base 5 so that there is less likelihood of the same becoming distorted by rough usage.

When the bails 6 and 7 are spread apart, as shown in Fig. 3, the carriers may be stacked with the bases 5 in nested relation, as previously mentioned, and in that way a large number may be shipped in the form of a more or less compact bundle.

In the construction illustrated in Fig. 4 the base 5' is U-shaped like the base 5 with upwardly diverging end walls to permit nesting of carriers in a similar manner, but the base 5' is made of wire instead of sheet metal. This base has a wire frame 26 which provides the two end rungs 27 and 28 with upwardly bent end portions 29 and 30 on which the loops or eyes 13 and 14 of the bails are attached for the same kind of loose fitting, easy working, pivotal sliding connections as are provided in the other form. The intermediate three wires 31 are parallel to the side rungs 27 and 28 and have upwardly bent end portions 32 which are welded at their upper ends to the cross portions 33 on the ends of the frame 26.

This construction affords generally the same advantages as the other, but the sheet metal base 5 is preferred over the wire base 5' because of its lower cost and better appearance. In both constructions the upwardly bent ends are in upwardly diverging relation to permit nesting, as in Fig. 3, and this outward inclination of the ends causes the looped ends of the bails to wedge to a tight fit when the bails are raised, thus making for better all around rigidity of the carrier.

It is believed the foregoing description conveys a good understanding of the objects and advantages of our invention. The appended claims have been drawn with a view to covering all legitimate modifications and adaptations.

We claim:

1. A bottle carrier comprising only three elements, namely, a base formed to provide a bottle-supporting bottom portion and opposed rigid upwardly projecting bottle retaining walls, and a pair of handle bails for carrying the carrier slidably pivotally attached directly to opposite sides of said base on said upwardly projecting walls for movement up and down relative to said base to and from an elevated carrying position, said

4

bails being interconnectible and disconnectible and constructed to serve when interconnected to cooperate with said bottle retaining walls to retain bottles on said base substantially the same in lowered position as when in elevated carrying position.

2. A bottle carrier comprising only three elements, namely, a base formed to provide a bottle-supporting bottom portion and opposed rigid upwardly projecting bottle retaining walls having rigid vertical guide portions on opposite ends of said walls, and a pair of inverted generally U-shaped handle bails for carrying the carrier having eyes formed on the lower end of the arms of the U's which are slidably pivotally attached directly to said guide portions to permit free up and down movement of said bails relative to said base to and from an elevated carrying position, the cross portions of the U's forming carrier handles and being arranged to be held together in one hand in carrying the carrier, said bails being interconnectible and disconnectible and constructed to serve when interconnected to cooperate with said bottle retaining walls to retain bottles on said base substantially the same in lowered position as when in elevated carrying position.

3. A bottle carrier comprising only three elements, namely, a base formed to provide a bottle-supporting bottom portion and opposed rigid upwardly projecting bottle retaining walls having rigid vertical guide portions on opposite ends of said walls, and a pair of inverted generally U-shaped handle bails for carrying the carrier having eyes formed on the lower end of the arms of the U's which are slidably pivotally attached directly to said guide portions to permit free up and down movement of said bails relative to said base to and from an elevated carrying position, the cross portions of the U's forming carrier handles and being arranged to be held together in one hand in carrying the carrier, said bails including horizontally extending side enclosure members for said base connecting the arms of the U's and cooperating with the upwardly projecting walls of the base in lowered as well as in raised position to retain bottles on the bottom portion thereof against lateral displacement.

4. A bottle carrier comprising only three elements, namely, a one-piece sheet metal base of rectangular form providing a bottle-supporting bottom portion and having opposed upwardly bent parallel portions, said bent-up portions having substantially vertical slots provided therein adjacent the opposite side edges thereof, and a pair of handle bails slidably pivotally attached directly to opposite sides of said base in said slots on said upwardly projecting portions for movement up and down relative to said base to and from an elevated carrying position, said bails being interconnectible and disconnectible and constructed to serve when interconnected to cooperate with said upwardly projecting portions to retain bottles on said base substantially the same in lowered position as when in elevated carrying position.

5. A bottle carrier comprising only three elements, namely, a one-piece sheet metal base of rectangular form providing a bottle-supporting bottom portion and having opposed upwardly bent parallel portions, said bent-up portions having substantially vertical slots provided therein adjacent the opposite side edges thereof, and a pair of inverted generally U-shaped wire handle bails for carrying the carrier having eyes

formed on the lower ends of the arms of the U's which are looped through the slots for a sliding pivotal connection of said bails directly to said base permitting free up and down movement of said bails relative to said base to and from an elevated carrying position, said bails being interconnectable and disconnectable and constructed to serve when interconnected to cooperate with said upwardly projecting portions to retain bottles on said base substantially the same in lowered position as when in elevated carrying position, the cross portions of the U's forming carrier handles and being arranged to be held together in one hand in carrying the carrier.

6. A bottle carrier comprising only three elements, namely, a one-piece sheet metal base of rectangular form providing a bottle-supporting bottom portion and having opposed upwardly bent parallel portions, said bent-up portions having substantially vertical slots provided therein adjacent the opposite side edges thereof, and a pair of inverted generally U-shaped wire handle bails for carrying the carrier having eyes formed on the lower ends of the arms of the U's which are looped through the slots for a sliding pivotal connection of said bails directly to said base permitting free up and down movement of said bails relative to said base to and from an elevated carrying position, the cross portions of the U's forming carrier handles and being arranged to be held together in one hand in carrying the carrier, said bails including horizontally extending side enclosure wire members for said base connecting the arms of the U's and cooperating with the upwardly projecting portions of the base in lowered as well as in raised position to retain bottles on the bottom portion thereof against lateral displacement.

7. A bottle carrier comprising a base of rectangular form providing a bottle-supporting bottom portion and opposed upwardly projecting wall portions, said upwardly projecting wall portions having substantially vertical openings provided therein adjacent the opposite side edges thereof, and a pair of handle bails slidably pivotally attached directly to opposite sides of said base in said openings on said upwardly projecting wall portions for movement up and down relative to said base to and from an elevated carrying position, the upwardly projecting wall portions of said base extending in an upwardly diverging relation so as to permit nesting of one base in another and so that said bails tend to become wedged in the upper ends of said slots in their elevated carrying position for greater rigidity of the carrier.

8. A bottle carrier comprising a base formed to provide a bottle-supporting bottom portion and opposed rigid upwardly projecting walls, rigid vertical guide portions on opposite ends of said walls, a pair of inverted generally U-shaped bails for carrying the carrier having eyes formed on the lower end of the arms of the U's which are slidably pivotally attached directly to said guide portions to permit free up and down movement of said bails relative to said base to and from an elevated carrying position, the cross portions of the U's forming carrier handles and being arranged to be held together in one hand in carrying the carrier, the cross portion of the one U being shorter than the cross portion of the other U so as to permit interfitting the upper ends of said bails in criss-cross relation, said cross portions being flexible and resilient, and a transverse projection on one of said cross-ports inter-

mediate the ends thereof arranged to be engaged behind the cross portion on the other bail when the bails are in criss-cross relation by flexing the latter cross portion intermediate its ends to permit such interengagement, whereby releasably to lock said bails together with their cross portions in abutment for use together as a single handle.

9. A bottle carrier comprising a base formed to provide a bottle supporting bottom portion and opposed rigid upwardly projecting end portions adapted to prevent bottles standing on the bottom portion of the base from being displaced off the ends of said base, a pair of bails for carrying the carrier slidably pivotally attached directly to opposite sides of said base on said upwardly projecting end portions for movement up and down relative to said base to and from an elevated carrying position, and means rigidly secured to said bails and movable up and down therewith relative to the base and cooperating with the upwardly projecting end portions adapted to prevent bottles standing on said base between the end portions from being displaced off the sides of said base.

10. A bottle carrier comprising a base formed to provide a bottle supporting bottom portion and opposed rigid upwardly projecting end portions adapted to prevent bottles standing on the bottom portion of the base from being displaced off the ends of said base, a pair of bails for carrying the carrier slidably pivotally attached directly to opposite sides of said base on said upwardly projecting end portions for movement up and down relative to said base to and from an elevated carrying position, means rigidly secured to said bails and movable up and down therewith relative to the base and cooperating with the upwardly projecting end portions adapted to prevent bottles standing on said base between the end portions from being displaced off the sides of said base, and means for detachably securing said bails together in operative relationship to one another.

11. A bottle carrier comprising a one-piece sheet metal base of rectangular form providing a bottle-supporting bottom portion and having opposed upwardly bent parallel portions to prevent bottles standing on the bottom portion of the base from being displaced off said base in the direction of said bent-up portions, said upwardly bent portions having substantially vertical slots provided therein adjacent the opposite side edges thereof, a pair of opposed bails slidably pivotally attached directly to said base in said slots on said upwardly bent portions for movement up and down relative to said base to and from an elevated carrying position, and means rigidly secured to said bails and movable up and down therewith relative to the base and cooperating with the upwardly bent portions to prevent bottles standing on said base between the upwardly bent portions from being displaced off the other two sides of said base.

12. A bottle carrier comprising a one-piece sheet metal base of rectangular form providing a bottle-supporting bottom portion and having opposed upwardly bent parallel portions to prevent bottles standing on the bottom portion of the base from being displaced off said base in the direction of said bent-up portions, said upwardly bent portions having substantially vertical slots provided therein adjacent the opposite side edges thereof, a pair of opposed bails slidably pivotally attached directly to said base in said slots on

said upwardly bent portions for movement up and down relative to said base to and from an elevated carrying position, means rigidly secured to said bails and movable up and down therewith relative to the base and cooperating with the upwardly bent portions to prevent bottles standing on said base between the upwardly bent portions from being displaced off the other two sides of said base, and means for detachably securing said bails together in operative relationship to one another.
